GARMENT HANGER

Lester E. Law, Connersville, Ind.

Application April 28, 1945, Serial No. 590,767

3 Claims. (Cl. 223—91)

This invention relates to garment hangers and more particularly to a clamping attachment for securing a garment to the cross wire connecting the inclined shoulder supporting portions of a coat hanger.

The invention has for its object to provide a clamping member in the form of a resilient bar adapted to detachably hook onto the hanger cross wire and to clamp a portion of a garment that is inserted between the clamping bar and the wire.

It is also an object of the invention to so form the clamping member that it can be quickly and easily attached to or detached from the coat hanger.

With the above and other objects in view, the invention may be said to comprise the garment hanger as illustrated in the accompanying drawing hereinafter described and particularly set forth in the appended claims, together with such variations and modifications thereof as will be apparent to one skilled in the art to which the invention pertains.

Reference should be had to the accompanying drawing forming a part of this specification in which:

Figure 1 is a side elevation showing the clamping member of the present invention employed to clamp the cuff portions of trousers to the cross wire of a coat hanger;

Fig. 2 is a section taken on the line indicated at 2—2 in Fig. 1;

Fig. 3 is a section taken on the line indicated at 3—3 in Fig. 1;

Fig. 4 is an elevation of the clamping member viewed as indicated at 4—4 in Fig. 1;

Fig. 5 is a side elevation of the clamping bar;

Fig. 6 is an end view of the bar taken as indicated at 6—6 in Fig. 5, and

Fig. 7 is a section taken on the line indicated at 7—7 in Fig. 5.

In the accompanying drawing the invention is shown applied to a conventional wire coat hanger that comprises a hook 1 and a loop that consists of inclined shoulder portions 2 and a cross wire 3 connecting the shoulder portions. The device of the present invention is a clamping member 4 in the form of an elongated bar formed of a strip of resilient material such as sheet metal. The bar 4 has attaching flanges 5 at the ends thereof that project from one side of the bar, each of the flanges 5 having a cross wire receiving slot 6 opening to a side edge of the flange and providing a wire retaining seat 7 at its inner

end that is offset outwardly toward the outer end of the flange and disposed substantially midway between the side edges of the flange.

As shown in Fig. 5 the bar is bowed longitudinally to provide a longitudinally convex garment engaging face on the side from which the flanges 5 project. The bar 4 is also bowed transversely so that the garment engaging face is transversely concave as well as longitudinally convex.

10 When the clamping member 4 is secured to the cross wire of a coat hanger with a portion of the garment inserted between the cross wire 3 and the bar 4, the bar 4 is flattened against the garment when it is hooked to the cross wire and the resilience of the bar 4 causes it to exert a pressure against the portion of the garment inserted between the bar 4 and the wire 3. By reason of the transversely concave form of the garment engaging face of the bar 4, the bar 4 has 15 opposite edges 8 that press against the garment above and below the cross wire 3 when the clamping bar is secured in place and bend the portion of the garment engaging the wire to more effectively hold the same. The longitudinally convex and transversely concave face of the bar provides a substantial clamping pressure and an effective gripping action on the garment clamped by the bar.

20 It will be apparent that the device of the present invention provides a very convenient and easily applied clamping member for securing a garment to a cross wire of a coat hanger, that this clamping member can be very quickly and easily removed when it is desired to detach the garment from the hanger and that the clamping member is adapted to be supported upon the cross wire of a coat hanger when not in use.

It is to be understood that variations and modifications of the specific device herein shown and described for purposes of illustration, may be made without departing from the spirit of the invention.

What I claim is:

45 1. A garment clamping member for attachment to a coat hanger cross wire comprising an elongated resilient bar having end flanges projecting to one side thereof and provided with cross wire receiving slots opening to side edges thereof, said bar having a longitudinally convex transversely concave garment engaging face on the side from which the flanges project, said bar being adapted to clamp a garment against a coat hanger cross wire and to deflect the engaged portion of the cross wire to set up an effective

gripping pressure along the length of portions of the bar and cross wire engaging the garment.

2. A garment clamping member for attachment to a coat hanger cross wire comprising an elongated resilient bar having end flanges projecting to one side thereof and provided with cross wire receiving slots opening to side edges thereof, said slots having wire seating portions at their inner ends located substantially midway between the side edges of the flanges, the face of said bar on the side from which the flanges project being longitudinally convex so as to deflect a coat hanger cross wire to the longitudinal curvature of said face when said bar is engaged with a coat hanger cross wire and thereby exert pressure upon a garment inserted between the bar and hanger cross wire, the face of said bar on the side from which the flanges project also being transversely concave to provide garment engaging edges above and below the cross wire.

3. A garment clamping member for attachment to a coat hanger cross wire comprising a bar formed of a resilient sheet metal strip bent to provide end flanges projecting to one side thereof and a garment engaging face on the side from which the flanges project that is longitudinally convex and transversely concave, said flanges having cross wire receiving slots extending inwardly from a side edge and provided with wire receiving seats at their inner edges that are offset outwardly toward the outer ends of the flanges and located substantially midway between the side edges of the flanges, said bar being adapted to clamp a garment against a coat hanger cross wire and to deflect the engaged portion of the cross wire to set up an effective gripping pressure along the length of portions of the bar and cross wire engaging the garment.
